ATTORNEY

UNITED STATES PATENT OFFICE.

GUSTAV HENDERSON, OF WOODSIDE, NEW YORK.

PAINTER'S TOOL.

SPECIFICATION forming part of Letters Patent No. 705,349, dated July 22, 1902.

Application filed March 26, 1902. Serial No. 100,037. (No model.)

To all whom it may concern:

Be it known that I, GUSTAV HENDERSON, a citizen of the United States, residing at Woodside, in the county of Queens, in the State of New York, have invented certain new and useful Improvements in Painters' Tools, of which the following is a specification.

My invention relates to painters' tools; and its novelty consists in the construction and adaptation of the parts, as will be more fully hereinafter pointed out.

Every painter needs a scraper in practicing his art, and each workman is commonly provided with one of a well-known shape and construction, consisting of a broad blade of sheet metal and a narrow wooden handle. In the course of my business I have found the need when painting a steep roof covered with shingles or otherwise for some means for supporting a paint-pot, so that it need not be held by an assistant or fellow workman. I have also found constant need for an extracting-tool in the nature of a claw-hammer to use in the removal of nails, staples, and the like.

The purpose of my invention is to combine in one implement a scraping-tool, a pot-holder, and an extracting-tool in such a manner that it will serve efficiently for all three purposes, be simple in construction, and of low cost.

In the drawings, Figure 1 is a top plan view of my combined tool with the parts folded together as they will be when the tool is used solely as a scraper. Fig. 2 is a central longitudinal section of the same, the handhold being shown in side elevation. Fig. 3 is a side elevation of the tool, on a smaller scale, showing its use as a pot-holder; and Fig. 4 is an enlarged detail perspective view of the part of the handle constituting the handhold and extracting-tool.

In the drawings, 1 is a broad-bladed scraper made of sheet metal thinned down or sharpened at its broadest extremity. This extends rearwardly and is turned upward at each side to form a handle 2, consisting of two plates 3, each of which is suitably enlarged at 4 and connected by a transverse pivot or pin 5.

At the rear the handle 2 is extended laterally and curved upward and then forwardly to form a handhold 6, the same being provided with lateral bifurcations 7, which con-

vert the handhold into a clawing-tool for the extraction of nails, staples, and the like. It will be observed that the scraping-blade, the handle, and the handhold are all made in the structure described of one piece of sheet metal, and this is the manner in which I prefer to make them; but it will be readily understood that variations may be made in the material employed without departing from the principles involved in such construction.

A pot-holder 7 is attached to the combined scraping-tool and extracting-tool just described. It consists of a longitudinal trough-like member 8, made by turning a piece of metal up at its sides 9. Each side is slotted, as at 10, to admit of the passage of the pin or pivot 5, and the sides are secured together at their upper extremity by a pin 11 and at their lower extremity by the transverse wooden slat 12, which serves as a stiffening-piece or brace as well.

The pin 5 serves as a hinge upon which the member 8 can turn. Each side plate 9 terminates at its lower extremity in a sharp point 13, which pass through suitable apertures provided in the bottom of the handle 2 when the handholder is in the position shown in Fig. 3.

The pot-holder is provided at its upper extremity with a snap-hook 14, made of two pieces of metal, one forming the hook proper, 15, and the other the spring-piece 16, these pieces being on each side of the pin or pivot 11.

The manner of using my combined tool as a pot-holder is illustrated in Fig. 3. In this figure, 17 and 18 are shingles arranged in the usual manner upon a sloping roof. The broad blade of the scraper is inserted under the uppermost shingle 17 and lies upon the shingle 18 immediately underneath. The pot-holder is swung upon the pivot 5 as a hinge until it assumes the position shown in the figure, the snap-hook 14 being extended as far as needs to be to hold the paint-pot 19, which is inserted under the edge of the hook in the manner shown in the figure and the bottom of which rests upon the upper part of the handhold 6. The sharp points 13 of the pot-holder, passing through the apertures in the handle of the scraper, are driven into the shingle 18 and prevent the tool from slipping downward.

The construction of the snap-hook 14 enables

a pot of any size to be carried by the tool, as the snap-hook can move up or down until a suitable height is obtained.

When it is no longer desired to use the combined tool as a pot-holder, the pot is taken off of the hook, which is then permitted to drop within the cavity formed between the slat 12 and the lower portion of the member 8. This member is then slid toward the rear of the tool, the slots 10 10 permitting such movement, until the points 13 13 pass under the forwardly-curved portion of the handhold.

What I claim as new is—

1. A painter's tool consisting of a scraping-blade and a handle therefor terminating in a transverse handhold provided with lateral bifurcations forming extracting-claws.

2. A painter's tool consisting of a scraping-blade a handle therefor and a hinged upwardly-projecting member provided with a hook at its upper end forming a pot-holder.

3. A painter's tool consisting of a scraping-blade, a handle therefor, a hinged upwardly-projecting member provided with a hook at its upper end forming a pot-holder and means for raising or lowering the hook.

4. A painter's tool consisting of a scraping-blade, a handle therefor, a hinged upwardly-projecting member provided with a hook at its upper end forming a pot-holder, and means for preventing the rotation of the pot-holder when in an upright position.

5. A painter's tool consisting of a scraping-blade, a handle therefor terminating in a

transverse handhold provided with lateral bifurcations forming extracting-claws and a hinged upwardly-extending pot-holder.

6. A painter's tool consisting of a scraping-blade, a handle therefor terminating in a transverse handhold provided with lateral bifurcations forming extracting-claws, a hinged upwardly-extending pot-holder and means for raising or lowering the latter.

7. A painter's tool consisting of a scraping-blade, a handle therefor terminating in a transverse handhold provided with lateral bifurcations forming extracting-claws, a hinged upwardly-extending pot-holder and means for preventing the rotation of the pot-holder when in an upright position.

8. A painter's tool consisting of a scraping-blade, a handle therefor terminating in a transverse handhold, an upwardly-extending pot-holder and a sheath for the latter when not in use.

9. A painter's tool consisting of a scraping-blade, a handle therefor, a hinged pot-holder extending upwardly therefrom, and means for maintaining the pot-holder in an upright position.

Witness my hand this 22d day of March, 1902, in the presence of two subscribing witnesses.

GUSTAV HENDERSON.
